CLAIM

The ornamental design for a makeup palette, as shown and described.

DESCRIPTION

FIG. 1 is a perspective view of the makeup palette showing the new design;

FIG. 2 is a top view thereof;

FIG. 3 is a bottom view thereof;

FIG. 4 is a front view thereof;

FIG. 5 is a rear view thereof; and,

FIG. 6 is a right side view thereof, the left side being a mirror image.

The line shading and the stippled shading shown in FIGS. 1, 2, and 4-6 illustrate a contrast in materials.
